UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

COMBINED COVER AND CENTER-PAGE-INSERT SHEET FEEDING AND FOLDING MECHANISM.

1,229,399.

Specification of Letters Patent. Patented June 12, 1917.

Application filed October 2, 1906. Serial No. 337,101.

To all whom it may concern:

Be it known that I, HOWARD M. BARBER, a citizen of the United States, and resident of Stonington, in the county of New London 5 and State of Connecticut, have invented a new and useful Improvement in Combined Cover and Center-Page-Insert Sheet Feeding and Folding Mechanisms, of which the following is a specification.

10 This invention contemplates novel mechanism arranged to cut combined previously printed cover and center page insert sheets from a source other than the main press and feed the same into position to be assembled 15 with the printed product as it comes from the press and subsequently folded together with said printed product and finally delivered to a predetermined point.

This invention further contemplates a 20 mechanism as above described which will cut and feed the combined previously printed cover and center page inserts from a web sheet supply.

In the accompanying drawings,

25 Figure 1 is a view of the machine in front elevation;

Fig. 2 is a vertical transverse section indicating diagrammatically the several parts which coöperate to produce the assembling 30 and folding together of the printed product and combined cover and center page insert sheets;

Fig. 3 is a diagrammatic view showing the 35 driving connections between the several parts;

Fig. 4 is an enlarged detail section taken immediately inside the framing and illustrating the parts of the mechanism at the front side of the machine for controlling 40 the movements of the grippers and folding devices on the several cylinders;

Fig. 5 is a detail section on the same scale as Fig. 4, taken adjacent to the back frame of the machine and showing the remaining 45 parts of the mechanisms for controlling the movements of the grippers and folding devices on the several cylinders, and

Fig. 6 is a detail section showing the box cam and truck roll arranged to control the 50 movement of the folding blade on one of the folding cylinders.

The framing of the machine is denoted by 10. This machine is shown as provided with

slitting mechanism mounted in position to divide the printed web as it comes from the 55 press into a plurality of webs. These webs are led around half-turners and rollers and are assembled into a group before reaching the cutting mechanism.

In the present instance I have shown the 60 slitting mechanism as comprising three slitters 12 arranged to slit the printed web as it comes from the press, into four webs which four webs pass around four half-turners 13 and from thence around rolls 14 65 and finally between rolls 15, 16. A pair of rotary smooth-edged cutters 17, 18 are mounted in the machine framing 10 in position to receive the assembled group of previously printed webs and cut sheets therefrom of the desired lengths.

Stationary sheet guides 19, 20 are arranged in position to receive the assembled group of previously printed webs from the cutting mechanism and direct the same between the folding cylinders 21, 22. The folding cylinder 21 is provided with a set of grippers 23 and the folding cylinder 22 with a set of grippers 24. The folding cylinder 21 is also provided with a folding 80 blade 25 which is arranged to coact with the floating folding jaw 26 carried by the folding cylinder 22. The delivery cylinder is denoted by 27 and it is provided with a floating folding jaw 28 arranged to co- 85 operate with a folding blade 29 mounted on the folding cylinder 22.

Carrying tapes 30, 31 are arranged in position to receive the signature from the delivery cylinder 27 and convey it to any suitable point, as, for instance, a suitable delivery mechanism 33 of the well known 90 packer type.

The mechanism for feeding the combined cover and center page insert sheets one at 95 a time to the folding cylinder 22 to be assembled together with the groups of the previously printed sheets from the press is as follows. The multicolor cover and center page insert web is rewound on a suitable 100 core 34 together with a blotter web 35 for preventing offset. This web roll is mounted in suitable supports in the machine framing 10. The blotter web 35 is wound upon a core 36 mounted in suitable bearings in the ma- 105 chine framing 10. The cover and center

page insert web is led from its roll into engagement with carrying tapes 37 which pass around rollers 38 and from thence the web is led to the cutting mechanism which in 5 the present instance comprises two rotary smooth-edged cutters 39, 40 arranged to cut the combined cover and center page insert sheets from the web. A pair of stationary guides 41, 42 are arranged in position to receive the web as it leaves the cutting mechanism and direct the same to the feeding cylinder 43. This feeding cylinder 43 is provided with a set of grippers 44 arranged to engage the advance edges of the sheets as 10 they come from the guides 41, 42 and deliver the same one by one to the set of grippers 24 on the folding cylinder 22 at the required times.

Proceeding to describe the driving and 20 operating mechanism for the several parts; the slitting mechanism and the rolls for feeding the plurality of previously printed webs to the cutters are driven from the press as follows. A vertical shaft 45 is driven 25 from a horizontal shaft 46 and it in turn drives the slitting roll 47. This slitting roll has a geared connection with the shaft 11 of the slitters 12. The slitting roll shaft drives the plurality of web feeding rolls 14 30 through a train of gears 48 which drives a cross shaft 49 having bevel gear connections with the shafts of the rolls 14. The web assembling rolls 15 and 16 are driven from one of the rolls 14 through a train of gears 50.

35 The rolls which wind up the offset web are denoted by 51, 52 and they are connected to the gear 54 of the delivery cylinder 27 through a train of gears 53. The gear 54 drives a pinion 55 on a driving roll shaft 40 56 of the carrying tapes 31. This gear 54 also meshes with a gear 57 fixed to the shaft 58 of the folding cylinder 22. This gear 57 drives a gear 59 on the shaft 60 of the folding cylinder 21. This gear 59 drives a gear 61 45 on the cutter 18 through an idler gear 62. This cutter 18 is also provided with a gear 63 which meshes with a gear 64 on the cutter 17. The gear 57 drives the cutter 40 through a train of gears 65, 66, 67, 68, and 50 the cutter 40 is provided with a gear 69 which meshes with a gear 70 on the cutter 39. The proportions of these gears are such that the cutters 39, 40 are driven at one-half the speed of the cutters 17 and 18. The 55 cover and center page insert web carrying tapes 37 are driven from the cutter 39, through gearing 71, 72. The cover and center page insert sheet feeding cylinder 43 is driven at varying speeds through irregular 60 gears 73, 74, fixed to the shafts of the cylinders 22 and 43 respectively, the shape of the said irregular gears being such that the cylinder 43 will be driven at the speed of the cover and center page insert web at the

time its grippers 44 engage the advance 65 edge of the web as it is delivered from the guides 41, 42, and at the surface speed of the folding cylinder 22 at the time the cover and center page insert sheet is transferred to the folding cylinder 22 and at an accelerated speed intermediate these two points.

The mechanism arranged to open the set of grippers 23 on the folding cylinder 21 every other revolution of the cylinder so that every other group of assembled sheets 75 from the press may be engaged by the said grippers, is as follows. A gear 75 is fixed to the shaft 60, which gear drives a gear 76 twice the size of the gear 75. This gear 76 is loosely mounted on a stud 77. A gear 78 80 is fixed to the gear 76 and is loosely mounted on the stud 77, which gear 78 drives a gear 79 of the same size as the gear 78, the gear 79 being loosely mounted on the shaft 60 of the folding cylinder 21. This gear 79 85 has fixed thereto a cam 80 loosely mounted on the shaft 60 of the cylinder 21, which cam is arranged to travel at one-half the speed of the cylinder 21 so that it will engage the gripper operating stud roller 81 90 every other revolution of the said cylinder.

The folding cylinder 22 is twice the size of the folding cylinder 21 and its set of grippers 24 are opened to receive the advance edge of the combined cover and center page insert sheet as it is delivered from the grippers 44 on the cylinder 43 by providing a stationary cam 82 arranged to engage the gripper operating stud roller 83. This set of grippers 24 is also opened at 100 the proper time to release the combined cover and center page insert sheet by means of a stationary cam 84 arranged in position to engage the gripper operating stud roller 83.

A stationary box cam 85 is arranged in 105 position to engage the stud roller 86 which controls the movement of the folding blade 25 carried by the folding cylinder 21. The floating folding jaw 26 on the folding cylinder 22 is opened to receive the folding 110 blade 25 on the folding cylinder 21 by the engagement of its operating stud roller 87 with a stationary cam 88. This floating folding jaw 26 is also opened at the proper time to release the assembled group of sheets 115 after their first fold, by the engagement of the stud roller 87 with a stationary cam 89. The floating of the folding jaw 26 is accomplished through the engagement of its stud roller 90 with the outer cam groove 91 120 in the stationary box cam 92.

The floating of the blade 29 on the cylinder 22 is accomplished by the engagement of its stud roller 93 with the inner cam groove 94 of the box cam 92. The opening of the floating folding jaw 28 in the delivery cylinder 27 is accomplished at the time of co-action with the folding blade 29 on the cyl-

inder 22, by means of a stationary cam 95 which engages the operating stud roller 96. The opening of the floating folding jaw 28 at the proper time to release the assembled 5 group of sheets after their second fold for delivering the sheets between the carrier tapes 30, 31, is accomplished through a stationary cam 97 which engages the said operating stud roller 96. The floating of the 10 folding jaw 28 is accomplished by means of a stationary cam 98, the groove 99 of which engages an operating stud roller 100 of the said floating folding jaw.

The opening of the set of grippers 44 on 15 the cylinder 43 for receiving the advance edge of the combined cover and center page insert sheet is accomplished by the engagement of a stationary cam 101 with operating stud roller 102. The opening of this set of grippers 44 at the proper time for delivering the advance edge of each combined cover and center page insert sheet to the grippers 24 on the cylinder 22, is accomplished by the engagement of a stationary cam 103 with the 25 said gripper operating stud roller 102.

The operation of the machine as herein described is as follows:

The web containing the multicolor cover and center page insert is carried over certain 30 of the feed rolls 38, beneath the carrier tapes 37 and from thence down between the cutters 39 and 40 and between the guides 41, 42. The advance edge of the web as it leaves the 35 guides 41, 42, is seized by the set of grippers 44 just before the combined cover and center page insert sheet is severed from the web by the cutters 39, 40. The cylinder 43 makes one revolution for each sheet fed and it has a varying speed as hereinbefore set forth, 40 whereby the surface speed of the cylinder 43 is the same as the speed of the web at the time the grippers 44 engage its advance edge, a faster speed immediately thereafter and a surface speed equal to the surface 45 speed of the cylinder 22 as the advance edge of the sheet is transferred to the set of grippers 24 on the said cylinder 22. This insures an absolute sheet register of the cover and center page insert sheet with the assembled 50 groups of sheets cut and fed from the press. The grippers 24 bring the combined cover and center page insert sheet into position to be folded with two groups of previously 55 printed sheets from the press as follows. As the printed web comes from the press, it is slit into a plurality of webs and then assembled and fed down between the cutters 17 and 18. These cutters 17 and 18 make two revolutions for each revolution 60 of the cutters 39 and 40, so that only one combined cover and center page insert sheet is supplied for each two groups of assembled sheets that are cut from the main webs. The folding cylinder 21 and its set of grippers 65 23 are so timed that the grippers 23 will

engage the advance edges of each alternate group of assembled sheets from the press so that one group of assembled sheets will be carried around the cylinder 21 at the proper time to meet the next succeeding group of 70 sheets, which succeeding group will be fed with its advance edges free down between the cylinders 21 and 22 outside of the combined cover and center page insert on the cylinder 22. The two groups of sheets and 75 the combined cover and center page insert sheet are folded together by the operation of the folding mechanism 25, 26, the grippers 23 and 24 having been opened. After the assembled groups of sheets from the press and 80 the combined cover and center page insert sheet have been folded once, a second fold is imparted thereto and the same transferred to the delivery cylinder 27 by the coöperation of the folding blade 29 and floating 85 folding jaw 28. It is to be understood that the floating folding jaw 26 is opened at the proper time to release the sheets from the cylinder 22. After the sheets have received their second fold, they are delivered between 90 the carrying tapes 30, 31 and from thence carried to any suitable delivery device 33.

What I claim is:

1. Means for cutting a sheet from a previously printed combined cover and center 95 page insert web, feeding means for said sheet, means for cutting a group of sheets from another previously printed web, feeding means for said group, means for associating the combined cover and center page 100 insert sheet with the said group of sheets and means for submitting the same to a plurality of folding operations.

2. Means for cutting a sheet from a previously printed combined cover and center 105 page insert web, feeding means for said sheet, means for cutting a plurality of groups of sheets from another previously printed web, feeding means for said groups, means for associating the combined cover 110 and center page insert sheet with the said groups of sheets, and means for submitting the same to a plurality of folding operations.

3. Means for cutting a sheet from a previously printed combined cover and center 115 page insert web, means for feeding said sheet to a predetermined point, means for cutting a group of sheets from another previously printed web and feeding it to said 120 predetermined point, means for associating said group with the combined cover and center page insert sheet, and means for submitting the same to a plurality of folding operations.

4. Means for cutting and feeding a plurality of groups of sheets from a web fed from a press, to a predetermined point, means for cutting sheets from a roll of previously printed combined cover and center 125 130

4
page insert web, and feeding them one at a time into position to be associated with the assembled plurality of groups of sheets cut from the previously printed web and 5 means for submitting the same to a plurality of folding operations.

5. Folding cylinders, means for cutting a sheet from a previously printed combined cover and center page insert web and feeding it to one of the folding cylinders, means for cutting a group of sheets from another previously printed web and feeding it to 10 said folding cylinders, means for associating said group with said combined cover and center page insert sheet and means for 15 folding the so associated sheets together.

6. Folding cylinders, means for feeding a group of sheets thereto, means for cutting sheets from a roll of previously printed 20 combined cover and center page insert web, and a cylinder arranged to feed the sheets one at a time to one of the folding cylinders to be associated thereon with the said group of sheets and folded together there- 25 with.

7. Folding cylinders, means for feeding a plurality of groups of sheets thereto, means for cutting sheets from a roll of previously printed combined cover and center 30 page insert web, and a cylinder arranged to feed the sheets one at a time to one of the folding cylinders to be associated thereon with the plurality of groups of sheets and folded together therewith.

8. Folding cylinders, means for feeding a group of sheets thereto, means for cutting sheets from a roll of previously printed combined cover and center page insert web, a cylinder arranged to feed the sheets one 35 at a time to one of the folding cylinders to be associated thereon with the group of sheets and folded together therewith, and means for imparting a variable speed to the feeding cylinder whereby it will be caused 40 to travel at the speed of the web at the time of engaging the advance edges of the same and at the surface speed of the folding cylinder at the time of transferring the sheet thereto.

9. Three folding cylinders, means for feeding a group of sheets to the first two folding cylinders, means for cutting sheets from a roll of previously printed combined cover and center page insert web, and feeding them one at a time to one of the first 50 two folding cylinders to be associated thereon with the said group of sheets, the first two folding cylinders being arranged to im-

part the first fold of the associated sheets and the second and third cylinders being 60 arranged to impart the second fold to the said sheets.

10. Three folding cylinders, means for feeding a plurality of groups of sheets to the first two cylinders, means for cutting 65 sheets from a roll of previously printed combined cover and center page insert web, and feeding them one at a time on to one of the first two folding cylinders to be associated thereon with the said plurality of 70 groups of sheets, the first two folding cylinders being arranged to impart the first fold to the associated group and the second and third cylinders being arranged to impart the second fold to the said sheets. 75

11. Two folding cylinders, means for feeding successive groups of sheets thereto, one folding cylinder being arranged to engage the first group of sheets, the second group of sheets being fed free between the 80 folding cylinders, means for cutting sheets from a roll of previously printed combined cover and center page insert web, and feeding them one at a time to one of the two folding cylinders to be associated thereon 85 with the two groups of sheets, the said two cylinders being arranged to impart the first fold to the associated sheets, and a third folding cylinder arranged to co-act with the second folding cylinder to impart the sec- 90 ond fold to the associated sheets.

12. The combination with a collecting cylinder, of a forwarding cylinder provided with folding means coacting therewith, means on the forwarding cylinder for taking sheets from the collecting cylinder, web delivery devices for said cylinders, web cutting devices, means for advancing a web, said means running at a lesser surface speed than the speed of the web delivery devices, 100 means for cutting sheets from this web, and means for bringing the sheets up to the speed of, and delivering them to the forwarding cylinder beyond the cutting line of the web cutting devices to be associated with 105 and to be folded off with the sheets delivered to it by the collecting cylinder.

In testimony, that I claim the foregoing as my invention, I have signed my name in presence of two witnesses, this first day of 110 October A. D. 1906.

HOWARD M. BARBER.
